METHOD AND APPARATUS FOR STRIPPING
YARN PACKAGES

Columbus C. Sumner, Elon College, N. C.

Application June 19, 1947, Serial No. 755,780

9 Claims. (Cl. 28—19)

1

This invention relates to means for stripping unused rovings from skewers such as used in spinning frames and in disintegrating the rovings into a mass of disconnected fibers so that such fibers can be immediately transferred to the picking room and passed through the pickers along with other fibers coming from the opening room.

It is a well-known fact that in spinning rooms, that when nearly all of the roving has been withdrawn from the tube disposed on the skewers in the spinning frame, that these are cast aside, and it is necessary to remove these unused rovings from the tubes before the tubes can be used again. Furthermore, it is desired to recover the fibers from these unused portions, and heretofore the practice has been to pass a sharp knife longitudinally of the tubes to sever the various convolutions of rovings to quickly remove them from the tubes. This has resulted not only in injury to the tubes, but also in a shortening of the fibers because long fibers are cut in this operation, and when the cut fibers are passed back to the opening room and the rovings reprocessed to pass them through a picker to prepare webs of fibers, there is much loss on account of the short fibers being lost during the processing operation.

It is an object of the present invention to provide means for withdrawing the unused portions of rovings from the tubes on skewers and the like and disintegrating the fibers as they are withdrawn and thus preserving the fibers in their original staple length without any injury whatever to the same.

Some of the objects of the invention having been stated, other objects will appear as the description proceeds, when taken in connection with the accompanying drawings, in which

Figure 1 is a top plan view of the apparatus with a portion broken away;

Figure 2 is a side elevation looking from the lower side of Figure 1 with portions broken away;

Figure 3 is an end view looking from the right-hand side of Figures 1 and 2;

Figure 4 is a vertical sectional view taken along the line 4—4 in Figure 3;

Figure 5 is a view similar to the right-hand end of Figure 2, but showing a modified form of the invention;

Figure 6 is an enlarged sectional plan view taken along the line 6—6 in Figure 2;

Figure 7 is an enlarged vertical sectional view of the top center portion of Figure 2.

Referring more specifically to the drawings, the numeral 10 indicates a container, preferably of rectangular shape and having wheels 11. The

2

container has screens 13 and 14 at each end thereof, and has a preferably circular opening 15 over which a suitable lid, not shown, may be placed and over which a bag can be placed for receiving the fibers within the box or container 10.

The container 10 has a lid 16 hingedly secured as at 17 to one of the side walls of the box 10. The lid 16 has a tubular member 20 penetrating the central top portion thereof near one end and 10 has a plurality of supporting stands 22 and 23 in which is mounted a pipe 24 having a cut-off valve 25 therein and the pipe 24 is adapted to be secured by means of a clamp 26 to a flexible air hose 27 connected to a suitable source of compressed air, not shown. The pipe 24 has a downwardly projecting restricted elbow 30 on its free end which projects down into the tubular member 20.

Mounted in the top of lid portion 16 and near 20 one end thereof is a plurality of spaced porcelain supports 33, each adapted to receive the lower pointed end 34 of a skewer 35. The skewers 35 are vertically arranged and the upper ends of these skewers are restricted as at 36 and these restricted portions are adapted to penetrate suitable holes 37 in a horizontally disposed board 38 which is supported near each end thereof by means of vertical supports 40 and 41. These skewers each have a tube 43 fitted thereon, and said tubes 43 before being fitted or slipped onto the skewers 35 have wound thereon a plurality of convolutions of rovings 44. These rovings are wound onto a cross-sectional diameter of several inches and these rovings are led from the skewers and tubes through a spinning frame apparatus.

35 When nearly all of the rovings are exhausted from a skewer or tube thereon, the same is removed. In the present embodiment of this invention, these skewers 35 with the tubes 43 thereon are arranged in the plurality of supports 33 as shown in the drawings, and one at a time, an end is withdrawn from the skewers and is passed down around the restricted tube 31 where a blast of compressed air not only withdraws the roving

40 44 from the tube 43 but also disintegrates the fibers of the roving and converts these fibers into a fluffy mass. When it is desired to remove the fibers from the container 10, the lid 16 may be raised upwardly and the operator may guide the

45 fibers out through the opening 15 into a bag secured around the annual rim 15.

Or if desired, instead of letting the disintegrated rovings fall into the container 10, there may be provided an arcuate tube 50 which will be secured to the lower surface of the lid 16 and

55

surround the tube 28, and the rovings as they are withdrawn from the tubes 43 will be disintegrated by the jet of air and will be forced loosely by the blasts of air along tube 50 and out the lower end thereof where a suitable bag can be disposed over the right-hand end of the tube 50 in Figure 5, or if desired, a suitable pipe can be connected to this tube 50, and the fibers can be carried by suction or otherwise to any desired part of the mill such as the opening room or the 10 picker room where they will be reprocessed.

The rate of feed of the roving 44 from a skewer 43 is regulated by the sharpness of the pointed lower end of the skewer. If the roving feeds too fast, the lower pointed end of the skewer can be flattened to thus cause the skewer to present more friction or drag to its rotation.

The suction of air around the compressed air nozzle 30 does not take any appreciable twist out of the roving, but when the roving comes in contact with the blast of air from the nozzle, the 20 roving is disintegrated.

The jet of compressed air from the nozzle 30 creates inwardly moving air currents around the nozzle and serves to feed the roving past the 25 nozzle 30.

In the drawings and specification there has been set forth a preferred embodiment of the invention, and although specific terms are employed, they are used in a generic and descriptive sense only, and not for purposes of limitation, the scope of the invention being defined in the 30 claims.

I claim:

1. Apparatus for stripping an unused roving from a skewer and disintegrating the fibers, comprising apparatus for holding for rotation a plurality of skewers each having a roving thereon, a tube through which the end of a roving is led, a pipe having an open end extending into the tube and having its other end connected to a suitable source of compressed air, whereby the stream of compressed air passing through the tube will unwind the roving from the skewer and disintegrate the same.

2. Apparatus for removing unused rovings from a yarn package comprising a container, means for rotatably supporting a plurality of yarn packages on the container, said container having a tube penetrating the cover of the same, a pipe for conducting compressed air and having an open end extending into the tube, the free end of a roving from a package being adapted to be inserted into the tube beside the nozzle, and the compressed air issuing from the nozzle serving to 40 unwind the roving from the package and to disintegrate the fibers thereof and to project them into the container.

3. That method of stripping a roving from a 60 yarn package which comprises supporting the package for rotation, passing the free end of a roving through a restricted member, forcing compressed air through the restricted member to unwind the roving from the package and to disintegrate the roving to convert the roving into fibrous bulk form.

4. Apparatus for stripping unused rounds of rovings from a yarn package comprising a container, a tube mounted in the top of the container and projecting into the container, and 70 compressed air nozzle projecting into the tube, whereby a free end of a roving can be inserted into the tube until it engages the compressed air

stream issuing from said nozzle to thereby unwind the roving from the package and to disintegrate the roving into fibrous form.

5. Apparatus for removing roving from yarn packages comprising a container, a tube disposed in said container, and a pipe of smaller dimensions than the tube passing into said tube and having an open end within the tube, means for passing a stream of compressed air through said pipe and through said tube, whereby when an end of roving is passed from a yarn package through said tube, the blast of air will not only unwind the roving from the yarn package but will disintegrate the fibers into a mass of loose fibers for future processing.

6. That method of removing a roving from a yarn package and disintegrating the roving and converting the same into loose fiber form, which comprises forcing a stream of air through a suitable opening feeding the end of a roving through said opening, and whereby the stream of air will continue to feed the roving through said opening by unwinding it from the yarn package and the blasts of air will also disintegrate the roving to reduce it to a mass of loose fibers.

7. Apparatus for removing unused portions of rovings from yarn packages which comprises means for rotatably supporting a plurality of yarn packages, a tube through which a roving is adapted to be projected, a nozzle extending into said tube and connected to a source of compressed air, whereby when a roving is fed into said tube with a jet of compressed air issuing from said nozzle and passing through said tube, the roving 35 will be unwound from the yarn package and will be disintegrated into a mass of fibers.

8. Apparatus for removing unused portions of rovings from skewers and the like which comprises means for rotatably supporting the skewers, a tube through which the free end of a roving is 40 adapted to be fed, an air jet in said tube for projecting a jet of compressed air through said tube to propel the roving through the tube and to unwind it from its skewer and to disintegrate the roving into a mass of fibers.

9. Apparatus for removing unused portions of rovings from skewers and the like comprising means for rotatably supporting a plurality of skewers, a container, a vertically disposed tube 50 disposed in the top of the container, a pipe connected to a source of compressed air and having an open end extending into said tube, whereby when a roving is led from a skewer and passed around said open end of the pipe and into said tube, the stream of air will unwind the roving from its skewer and propel it through the tube and disintegrate the fibers to project them into the container as a mass of loose fibers.
